UNITED STATES PATENT OFFICE.

HARRY W. PONTING AND ARTHUR J. WATLING, OF JUNCTION CITY, KANSAS.

COMBINATION-LOCK.

1,347,708.

Specification of Letters Patent. Patented July 27, 1920.

Application filed May 26, 1917. Serial No. 171,247.

To all whom it may concern:

Be it known that we, HARRY W. PONTING and ARTHUR J. WATLING, citizens of the United States, residing at Junction City,

5 in the county of Geary, in the State of Kansas, have invented a new and useful Combination-Lock, of which the following is a specification.

This invention relates to locks for steering posts and steering mechanisms of automobiles, motor cycles and the like and has for its object the provision of novel means whereby rotary members, that is to say the steering shafts of automobiles or motor 10 cycles may be locked against rotation, the said invention having for its further object the provision of novel means for holding the locking member and in this instance a locking bar in locked or unlocked position.

20 A still further object of this invention is to provide novel permutation members associated and coöperating with the locking bar.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which—

35 Figure 1 illustrates a view in elevation of a fragment of a steering mechanism of an automobile showing the application of the invention to the steering column;

Fig. 2 illustrates a plan view of the lock 40 casing and parts associated therewith;

Fig. 3 illustrates an enlarged detail view of one of the dials and the indicator associated therewith;

Fig. 4 illustrates a view in elevation, 45 partly in section of the steering mechanism and the lock applied thereto, the casing of the lock being broken away;

Fig. 5 illustrates a sectional view on the line 5—5 of Fig. 4;

50 Fig. 6 illustrates a sectional view on the line 6—6 of Fig. 4;

Fig. 7 illustrates a detail view in elevation of one of the dial shafts;

Fig. 8 illustrates an underneath plan view 55 of the casing;

Fig. 9 illustrates a detail view of the locking bolt; and

Fig. 10 illustrates a vertical sectional view of the lock.

In the present embodiment of the invention, a face plate 15 and a back plate 16 are employed, the same being connected by posts 17 which are threaded in the face plate, the said back plate having apertures 18 for the reception of the posts, the ends of the said posts having heads which can be engaged by a screw driver or the like by turning the posts to thread them in the face plate, and a casing 20 closes the space between the two plates. The back plate has recesses 21 constituting bearings for the dial shafts 22, the said shafts being enlarged intermediate their lengths and the said enlarged portions each being provided with a slot such as 23. The upper ends of the dial shafts 25 extend through apertures 24 in the face plate and terminate in knurled heads 25 by which the shafts may be rotated. Each shaft has a pointer or indicator 26 applied to it, so that it may be rotated with relation 30 to the face 27 of the dial, so as to bring the pointer into position with relation to any of the numbers. The pointer may be set on the dial shaft in such relation to the slot in the shaft as to cause the pointer of 35 the indicator to reach a certain position or number when the slot is in position to align with one of the studs or pins to be presently described which project or radiate from the locking bolt. Tension devices such 40 as springs 28 are applied to the shafts and bear against the under surface of the face plate so as to prevent rattling or vibration of the said shafts while the vehicle is moving and in order to form a bearing for the 45 tension members or springs, the dial shaft 22 is provided with a shoulder 29 on which the spring is seated.

The spring may comprise a curved piece of metal having means for applying it to 50 the shaft, and if the spring is provided with an aperture to receive the shaft, it will fulfil the requirements.

A washer is interposed between the indicator 26 and the dial to permit the indicator to move over the surface of the dial without rubbing the said dial and it is to be understood that each of the dial shafts and indicators is supplied with the same structural features.

105

110

The back plate has a central aperture 31, the wall of which has oppositely disposed fins 32 which enter slots 33 in the bolt 34 to prevent the said bolt from turning and the locking bolt has studs or pins 35 which are adapted to enter the slots 23 of the dial shafts when the said dial shafts have been set to free the locking bolt. The locking bolt has a knurled head 36 secured to it by 10 a pin 37 and pins 38 are employed for securing the knurled heads to the dial shafts for convenience in operating these parts.

The locking bolt has a shoulder 39 which is engaged by a spring 40 encircling the 15 said bolt and this spring is adapted to bear against the inner surface of the face plate when the locking bolt is withdrawn in order to hold the locking bolt against vibration, and it will be apparent that when the 20 locking bolt is withdrawn, the studs or pins 35 rest on the shoulders 41 of the dial shafts.

The construction and operation of the device will, it is thought, be understood from the foregoing description and it will be apparent that a number of combinations may 25 be had by the adjustment of the indicators on the shafts in certain relation to the slots of the dial shafts and that when the locking bolt is projected or forced inwardly and the 30 dial shafts are turned so that the slots thereof are out of alinement with the pins, the said pins will strike or engage the shoulders 42 of the said dial shafts if any attempt is made to withdraw the locking bolt.

35 Therefore, the locking bolt which enters a recess or socket 43 of the steering post 44 will prevent rotation of the steering shaft and an automobile or motor cycle cannot be steered.

40 We claim—

1. In a lock for automobiles, motor cycles and the like, a face plate, a back plate, a casing associated with the face plate and back plate to form a housing, posts interposed between the face plate and the back

plate, said back plate having recesses forming bearings and the face plate having apertures, dial shafts rotatable in the recesses and apertures, said dial shafts having longitudinally extending slots, shoulders on the 50 said shafts, springs interposed between the shoulders and the face plate, said springs each comprising an apertured member, lying on a shoulder of a shaft and laterally curved with its edge engaging the plate, a 55 locking bolt slideable in the casing, means for holding the locking bolt against rotation, pins radiating from the locking bolt and adapted to oscillate in the slots of the shafts, shoulders on the upper ends of the 60 shafts adapted to engage the pins, and shoulders near the lower ends of the shafts for engaging the pins.

2. In a lock for automobiles, motor cycles and the like, a face plate and back 65 plate, a casing associated with the face plate and back plate to form a housing, posts interposed between the face plate and the back plate, said back plate having recesses forming bearings and the face plate having 70 apertures, dial shafts rotatable in the recesses and apertures, said dial shafts having longitudinally extending slots, shoulders on the said shafts, springs interposed between the shoulders and the face plate, a locking 75 bolt slideable in the casing, means for holding the locking bolt against rotation, pins radiating from the locking bolt and adapted to slide in the slots of the shafts, shoulders on the upper ends of the shafts adapted 80 to engage the pins, shoulders near the lower ends of the shafts for engaging the pins, a shoulder on the locking bolt, and a spring engaging the said shoulder and adapted to engage the inner surface of the face plate 85 when the pins of the locking bar are in engagement with the outer shoulders of the shafts.

HARRY W. PONTING
ARTHUR J. WATLING.
